UNITED STATES PATENT OFFICE.

GEORGE H. BROWN AND HENRY J. WELTEROTH, OF BLOSSBURG, PA.

APPARATUS FOR ADJUSTING THE BEAT OF PENDULUM-CLOCKS.

SPECIFICATION forming part of Letters Patent No. 292,282, dated January 22, 1884.

Application filed August 4, 1883. (Model.)

To all whom it may concern:

Be it known that we, GEORGE H. BROWN and HENRY J. WELTEROTH, of Blossburg, in the county of Tioga and State of Pennsylvania, 5 have invented a new and Improved Pendulum-Clock, of which the following is a full, clear, and exact description.

The object of our invention is to provide means for the adjustment of the verge or pallet relatively with the escapement and pendulum-rod whereby the clock may be set in perfect beat when resting on an unlevel surface or support.

The invention consists in the combination, 15 with the escapement-wheel, the verge or pallet, and the pendulum-rod, of an adjusting-screw journaled in bearings on the verge-fork, so as to act when turned in one direction or the other to deflect the verge-fork with relation 20 to the pendulum-rod and the verge or pallet, to cause the verge or pallet-teeth to be properly engaged by the escapement-wheel, should the clock set out of level either way.

The invention consists, also, in special constructions of the parts in detail and as combined with each other, all as hereinafter fully described and claimed.

Reference is to be had to the accompanying drawings, forming a part of this specification, 30 in which similar letters of reference indicate corresponding parts in all the figures.

Figure 1 is a front view of my improvement as applied to use. Figs. 2 and 3 are enlarged detail front views of the verge-fork bearings 35 and connections, and Fig. 4 is a sectional plan view on the line $x-x$, Fig. 2.

We represent in Fig. 1 only as much of a pendulum-clock and its movement as is necessary to set forth our improvement, which consists, in this example, in fitting the verge-fork 40 a with a screw-rod, b , which works in bearings c , d , carried by the fork of the verge.

The verge or pallet f , to which the fork a is attached, is pivoted at f' , to oscillate by engagement with it of the escapement-wheel g of 45 the clock-movement. The lower end of the verge-fork has the usual eye or loop, h , through which passes the rod i of the pendulum, which has the common flexible connection, j , with the 50 movement-frame, and may be of any approved construction.

The verge-fork bearing c consists of a part, c' , fixed rigidly to the verge-fork a , and a part, c'' , pivoted to the part c' at k , to swing thereon in vertical plane. The part c'' is screw-tapped 55 for a nut to receive the screw-threaded portion b' of the rod b , which may work up and down therein, the nut c'' accommodating itself on the pivot k to any deflection of the fork a of the verge.

The verge-arm bearing d consists of a part, d' , fixed to fork a , and having an eye, d'' , through which the screw-rod b can move loosely and rotate freely, collars l being fixed to rod b at each side of eye d'' , so that any turning of the 65 rod b in its nut c'' will act to deflect or bend the verge-fork and throw the verge or pallet f to the right or left, as required. The bearing d may have two eyes, d'' , one at each side of a single fixed collar, l , on the rod b , if desired. 70

The operation is as follows: Supposing the screw-rod b to have at b' a right-hand thread, if the clock stands on a surface inclining downward toward the left, the rod b will be turned 75 toward the right, thereby bowing out the verge-fork a from a normal position by shortening the distance between bearings c , d and throwing the tooth f'' of the verge or pallet f over to the left, while, if the clock stands inclining 80 downward toward the right, the screw b will be turned toward the left for opposite effect on the verge-fork by a drawing downward of verge or pallet tooth f'' , and correspondingly raising the opposite tooth, f'' , as will readily 85 be understood. The verge or pallet f may thus always be relatively adjusted to properly be acted on by the escapement-wheel to set and keep the clock in perfect beat.

Our improvement is simple and inexpensive, 90 and may readily be applied to old clocks or those in course of manufacture with like useful results.

Having thus described our invention, we claim as new and desire to secure by Letters 95 Patent—

1. In a pendulum-clock, the combination, with an elastic verge or pallet fork, of a screw for bowing the same, substantially as and for the purpose set forth.

2. A pendulum-clock constructed with a verge or pallet fork, a , fitted with bearings c , d

and screw-rod *b*, the verge or pallet being pivoted at *j'* to be engaged by the escapement-wheel *g*, and the verge-arm being connected at *h* with the pendulum-rod *i*, substantially as shown and described.

3. In pendulum-clocks, the verge or pallet fork *a*, constructed with bearings *c d*, a screw-rod, *b*, and an eye, *h*, substantially as shown and described.

4. In pendulum-clocks, the verge or pallet fork, *a*, having a bearing, *e*, formed of part *c'*,

fixed to arm *e*, and a pivoted nut, *c''*, a bearing, *d*, fixed to arm *e*, and the adjusting screw-rod *b*, held rigidly lengthwise in the bearing *d*, and adjustable in the bearing *e* for deflecting the verge or pallet fork, substantially as shown and described. 15
